CLAIM

The ornamental design for tubular packaging for deadbolt, as shown and described.

DESCRIPTION

FIG. 1 is a perspective view of tubular packaging for a deadbolt;

FIG. 2 is a top view thereof (the bottom view being identical to the top);

FIG. 3 is a front view thereof (the back view being identical to the front);

FIG. 4 is an exploded perspective view thereof; and, FIG. 5 is a right side view thereof (the left side view being identical to the right).

The broken line showing of the environment is for illustrative purposes only and forms no part of the claimed design.
